CLAIM

The ornamental design for a safety switch mounting plate, as shown and described above.

DESCRIPTION

FIG. 1 is a front elevational view of a safety switch mounting plate showing my new design with the two members separated;

FIG. 2 is a top plan view thereof;

FIG. 3 is a right side elevational view thereof, the left side elevational view thereof being a mirror image;

FIG. 4 is a rear elevational view thereof; and,

FIG. 5 is a front and upper left perspective view thereof.

FIG. 2.

FIG. 1.

FIG. 3.

FIG. 4.

FIG. 5.
